CLAIM

I claim, the ornamental design for a portable securing syringe device, as shown and described.

DESCRIPTION

FIG. 1 is a perspective view of a portable securing syringe device showing my design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view shown in a position of use.

The broken lines in the drawings illustrate portions of the environment of the portable securing syringe device and form no part of the claimed design.
